(57) **CLAIM**

The ornamental design for a shooting target, as shown and described.

DESCRIPTION

FIG. 1 is a front, right, and top perspective view of a shooting target, showing my design.

FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled 9 in FIG. 1 comprising a ring.

FIG. 10 is a partial enlarged view of an area labeled 10 in FIG. 1 comprising a part of a net pocket.

FIG. 11 is a partial enlarged view of an area labeled 11 in FIG. 1 comprising a part of a panel.

FIG. 12 is a partial enlarged view of an area labeled 12 in FIG. 2 comprising a hanger piece; and,

FIG. 13 is another front, right, and top perspective view of the shooting target of FIG. 1, showing a using state.

The dot-dash broken lines in FIGS. 1, 2 and 9-12 depict the boundaries of the enlargements that form no part of the claimed design. The evenly spaced broken lines in FIGS. 1-9 and 11-13 depict portions of the shooting target that form no part of the claimed design. The evenly spaced broken lines in FIG. 13 depicting the environment of guns and projectiles form no part of the claimed design.

1 Claim, 13 Drawing Sheets
